[57] CLAIM

The ornamental design for a mounting bracket for a compact optical scanner, as shown.

DESCRIPTION

FIG. 1 is a top, front right side perspective view of a mounting bracket for a compact optical scanner showing our new design;

FIG. 2 is a top, rear, right side perspective view thereof;

FIG. 3 is a bottom plan view thereof;

FIG. 4 is a top plan view thereof;

FIG. 5 is a front elevational view thereof;

FIGS. 6 and 7 are respectively left and right side elevational views thereof;

FIG. 8 is a rear elevational view thereof.

Fig. 1

FIG. 2.

FIG. 3.

FIG. 4.

FIG. 5.

FIG. 6.

FIG. 7.

FIG. 8.
